CORPORATION OF NEW JERSEY

ROCK DRILL

Application filed August 14, 1928. Serial No. 299,493.

This invention relates to rock drills, but more particularly to valve mechanism for effecting the distribution of pressure fluid to the cylinder of rock drills of the hammer type.

The objects of the invention are to simplify the construction of rock drills of this type, to insure an abundant admission of pressure fluid to the cylinder with a minimum lift of the valve or valves, to lessen the chances of injury to the valves, to render the valve mechanism inexpensive to manufacture and maintain, and to obtain a rapid and positive action of the valve mechanism and consequently also of the percussive element of the rock drill.

Other objects will be in part obvious and in part pointed out hereinafter.

In the drawings accompanying the specification and in which similar reference characters refer to similar parts,

Figure 1 is a sectional elevation of a portion of a rock drill showing one form which the invention may assume in practice,

Figure 2 is a similar view showing a modification of the invention,

Figure 3 is a transverse view taken through Figure 2 on the line 3—3 looking in the direction indicated by the arrows and showing the arrangement of the valve seats,

Figure 4 is an enlarged transverse view taken through Figure 2 on the line 4—4 looking in the direction indicated by the arrows,

Figure 5 is a longitudinal sectional elevation of a rock drill showing a modified form of the invention, the view being taken through Figure 6 on the line 5—5 looking in the direction indicated by the arrows,

Figure 6 is a transverse view taken through Figure 5 on the line 6—6 looking in the direction indicated by the arrows, and showing the arrangement of the valves,

Figure 7 is a perspective view of a valve, and

Figure 8 is a similar view of a valve guide.

Referring to the drawings and at first more particularly to Figure 1, A designates a cylinder having a piston chamber B in which is disposed a reciprocating hammer piston C for delivering blows to a working implement (not shown). The front end of the piston

chamber B is provided with a closure in the form of a front cylinder washer D having a bore E for guiding a stem or extension F of the piston C. A free exhaust port G in the cylinder is controlled by the piston C.

A suitable closure is provided for the rearward end of the piston chamber B in the form of a plate H. The plate H is disposed in an enlarged bore J in the rearward end of the cylinder A and forms a seat for a back head K which may be secured to the cylinder by any suitable means, such as side bolts (not shown).

Preferably the back head K serves as a housing for the head L of a rifle bar O which extends through the plate H and slidably engages the piston C in a well known manner. The rifle bar L may be provided with the usual spring pressed pawls P adapted to engage teeth Q of a rotation ratchet R secured fixedly in a recess S in the back head K in which the head L also lies.

The parts so far described and their functions are well known and are herein only briefly referred to in order to explain more clearly the present invention and its application and advantages.

In accordance with the present invention a valve chest designated generally by T is disposed in the bore J to seat on an end wall U in the cylinder A and in turn forms a seat for the plate H. The valve chest T comprises a rearward end plate V, a forward end plate W and an intermediate plate X. The plates V, W and X as well as the plate H may be securely clamped in the operative position by means of the side bolts which exert a pressure on the back head. Any other suitable means may, however, be provided for maintaining these parts in the operative position.

The plate X may be a flat plate of uniform thickness throughout and is provided with a plurality of valve chambers Y in which are disposed valves Z in the form of thin flat disks or plates guided only on their peripheries by the chambers Y. At the rearward sides of the valve chambers Y and on the plate V are valve seats b which act as stops for the valves Z.

The valve seats b are preferably of consid-

erably smaller diameter than the valves Z so that an annular area of the rearward ends of the valves Z will be at all times exposed to pressure fluid. Similarly, the plate W is provided with valve seats c for the front ends 5 of the valves Z, said valve seats c being of the same proportions and conformation as the valve seats b so that a similar annular area on the front surfaces of the valves Z will also be constantly subjected to live pressure fluid.

By thus forming the valve seats b and c, the shoulders d and e will be formed around the valve seats b and c and said shoulders are only slightly spaced from the plate X to assure the restriction of the pressure fluid entering the valve chambers Y.

In the construction shown inlet passages f lead from the rearward ends of the valve chambers Y through the plate V to the rearward end of the piston chamber B. Front inlet passages g lead from the valve seats c through the plate W and through the cylinder A to the front end of the piston chamber B for conveying pressure fluid thereto to impel the piston C in a rearwardly direction.

The pressure fluid utilized for actuating the piston C may be introduced into the drill at a point adjacent a throttle valve h disposed in this instance in a valve chamber j in the back head K. The throttle valve h is provided with a central chamber k and has a port o to afford communication between the chamber k and a passage p leading from the throttle valve chamber j to a supply reservoir q located in this instance in the back head K. Pressure introduced into the supply reservoir q is conveyed through the valve chest by supply passages r which communicate at their other ends with a supply chamber s surrounding in this instance the valve chambers Y. The supply chamber is of an annular shape and is of a depth to lie both below and above the plate X and of a width to communicate with each valve chamber Y at opposite sides thereof so that in effect it forms a portion of each valve chamber. This assures an abundant supply of pressure fluid to each inlet passage immediately after the valves shift. The supply passages r however, extend to the lowermost point of the supply chamber so that both sides of the valves Z will be constantly exposed to pressure fluid in a manner to be more fully described hereinafter.

In order to assure compactness and a minimum weight of the rock drill the plates X, V and W comprising the valve chest are provided with bores t of the same diameter as the piston chamber B for which the bores t form a continuation so that the piston C may reciprocate through the valve chest.

The operation of the form of the invention so far described is as follows: With the throttle valve h in the open position and the

valves Z and the piston C in the positions illustrated, pressure fluid flowing from the supply reservoir q through the supply passages r into the supply chamber s will flow through the restricted spaces between the shoulders d and the rearward surface of the plate X into the valve chambers Y and thence through the rearward inlet passages f into the rearward end of the piston chamber B to impel the piston C forwardly against the working implement. While the valves are in the position described the annular areas of the valves Z lying outside of the valve seats c are exposed to live pressure fluid.

During the passage of pressure fluid into the rearward end of the piston chamber B the entire rearward surfaces of the valves Z are exposed to pressure fluid so that the valves Z will remain firmly seated on the valve seats c. The valves Z will remain in this position until the piston C approaches the forward end of the piston chamber B.

As the piston C covers the exhaust port G the air in the front end of the piston chamber B will be compressed and such compression flowing through the inlet passages g will act against the forward surfaces of the valves Z tending to throw the valves Z rearwardly against the seats b. Shortly prior to the time the piston C delivers its blow against the working implement the free exhaust port G will be uncovered by the piston. Pressure fluid used for throwing the piston C forwardly will then exhaust to the atmosphere through the exhaust ports G. This will cause a reduction in pressure on the rearward ends of the valves Z due to the manner in which the flow of pressure fluid into the valve chambers is restricted. The valves will then be thrown rearwardly against the seats b by the pressure fluid and the compression acting against the forward surfaces of the valve.

With the valves Z thus reversed pressure fluid will flow into the valve chambers Y through the restricted spaces between the shoulders e and the forward surface of the plate X into the valve chambers Y, thence through the inlet passages g into the front end of the piston chamber B to impel the piston C rearwardly.

The air entrapped in the rearward end of the piston chamber by the piston will of course also be compressed and will act against the rearward surfaces of the valves Z. At the same time the areas of the valves lying outside of the seats b are exposed to live pressure fluid. After the piston C has travelled rearwardly a sufficient distance to uncover the exhaust port G the pressure fluid will be exhausted from the front end of the piston chamber to the atmosphere. This will cause a sudden drop of pressure in the forward surfaces of the valves Z and the valves will thence be moved forwardly against the seats c by the compression and the live air acting

against the rearward surfaces of the valves.

In the modification shown in Figures 2 to 4 inclusive, the cylinder A is provided at its rearward end with a bore *u* of sufficient depth to receive the valve chest *v* and a rotation ratchet *w* disposed in this instance on the valve chest *v*. The rotation ratchet *w* forms a seat for a back head *x* which may be secured to the cylinder A in any well known manner. The valve chest *v* comprises forward and rearward end plates *y* and *z* respectively and an intermediate plate 2. Seated on the rearward surface of the plate *z* is a plate 3 to form a seat for the rotation ratchet *w* and for the head *L* of the rifle bar *O*. In this modification the back head *x* is also provided with a supply reservoir 4 which is in constant communication with the supply chamber *s* through supply passages 5 leading 20 through the rotation ratchet *w* and the plates 3, *z*, 2 and *y*.

In the construction shown in this modification the plate *y* forms a closure for the rearward end of the piston chamber B and pressure fluid is admitted to the front end of the piston chamber through an inlet passage 6 in the cylinder A communicating at its rearward end with a chamber 7 preferably formed in the plates 3 and *z*. From the chamber 7 to the ends of the valve chambers Y lead passages 8 for conveying pressure fluid from the rearward ends of the valve chambers Y to the chamber 7. The admission of pressure fluid to the rearward ends of the piston chamber B is effected through inlet passages 9 formed in the plate *y* and opening directly into the piston chamber B.

The plates comprising the valve chamber *v* such as the plates *y*, *z*, 2 and 3 are each provided with bores 10 to receive the rifle bar *O* and form a guide therefor. The construction of the plates comprising the valve chambers and the valve seats in this modification is the same as that described in connection with the previous modification. The operation is also practically the same and differs principally in that the chamber 7 may act as an expansion chamber so that as the piston C approaches the front end of the piston chamber an ample chamber is provided for the air compressed in the front end of the piston chamber and the piston C may therefore deliver a heavy blow against the working implement before sufficient pressure fluid is admitted to the front end of the piston chamber to retard the forward movement of the piston.

The general arrangement of the parts comprising the modification shown in Figures 5 to 8 inclusive is substantially like that illustrated in Figure 2, that is, the rotation ratchet *w* is disposed in a bore 11 in the rearward end of the cylinder A and forms a seat for the back head *x* which also has a supply reservoir 4. Disposed in the bore 11

and forwardly of the rotation ratchet *w* is a plate 12 which forms a seat for the front end of the rotation ratchet *w* and for the head *L* of the rifle bar *O*.

The plate 12 is in turn seated on a plate 13 in the bore 11. The plate 13 forms a portion of the valve chest and in the forward end of the bore 11 is a plate 14 which serves both as a part of the valve chest and as a closure for the rearward end of the piston chamber B.

In this construction the plates 13 and 14 are provided in their adjacent surfaces with annular supply chambers 15 which communicate with the supply reservoir 4 through supply passages 16 in the rotation ratchet *w* and the plates 12 and 13. The supply chambers 15 are formed in both the plates 13 and 14 so that the opposite sides of the valves Z and the valve chambers Y may be constantly exposed to pressure fluid.

On the inner surface of the annular supply passages 15 are disposed valve guides 17 to receive the valves Z. In the peripheries of the valve guides 17 are rows of small ports 18, the ports 18 being located adjacent the valve seat *b* and the ports 19 adjacent the valve seats *c*. These ports 18 and 19 are of such cross sectional area that the pressure fluid is somewhat restricted during its passage from the supply chambers 15 into the valve chamber Y.

Preferably the valve guides 17 are of a height equal to the depth of the supply chambers 15 so that when the parts are assembled in the drill the valve guides 17 will be held against endwise movement. The pressure fluid is in this instance conveyed to the rearward end of the piston chamber B by inlet passages 20 formed in the plate 14 and opening at their inlet ends into the valve seats *c*. The admission of pressure fluid to the front end of the piston chamber B is effected through an inlet passage 21 formed in the cylinder A and communicating at its rearward end with a chamber 22 formed in the adjacent surfaces of the plates 12 and 13. From the chamber 22 lead passages 23 for conveying pressure fluid from the rearward ends of the valve chambers Y to the chamber 22.

The operation of this modification is substantially like that previously described and this modification differs from the prior described modifications principally in the manner in which the valves Z are guided.

We claim:

1. In a fluid actuated rock drill, the combination of a cylinder and a piston in the cylinder, an exhaust port for the cylinder, a valve chest having a plurality of valve chambers and a supply passage, distributing valves in the valve chambers, a bore in the valve chest to slidably receive the piston, inlet passages leading from the valve chamber to the cyl- 125
- 130

inder, and a valve in the valve chamber controlling communication between the supply and inlet passages.

2. In a fluid actuated rock drill, the combination of a cylinder and a piston in the cylinder, an exhaust port for the cylinder, a valve chest in the cylinder having a plurality of valve chambers and a supply passage, distributing valves in the valve chambers, a bore in the valve chest to slidably receive the piston, inlet passages leading from the valve chamber to the cylinder, and a valve in the valve chamber controlling communication between the supply and inlet passages.

3. In a fluid actuated rock drill, the combination of a cylinder and a piston, an exhaust port for the cylinder, a rifle bar for rotating the piston, a valve chest encircling the rifle bar and having a plurality of valve chambers, a supply passage affording communication between the valve chambers and a source of pressure fluid supply, inlet passages leading from the valve chambers to the cylinder, and valves in the valve chambers controlling communication between the supply and inlet passages.

4. In a fluid actuated rock drill, the combination of a cylinder and a piston, an exhaust port for the cylinder, a rifle bar for rotating the piston and having a head, a valve chest encircling the rifle bar and forming a seat for the head, a plurality of valve chambers in the valve chest, a supply passage constantly conveying pressure fluid from a source of supply to the valve chambers, inlet passages leading from the valve chambers to the cylinder, and valves in the valve chambers for controlling the flow of pressure fluid from the supply passage to the inlet passages.

5. In a fluid actuated rock drill, the combination of a cylinder having a piston chamber and a piston in the piston chamber, a rifle bar for rotating the piston, a valve chest in the cylinder encircling the rifle bar and having a bore forming a continuation of the piston chamber, a plurality of valve chambers in the valve chest, a supply passage for conveying pressure fluid from a source of supply to the valve chambers, inlet passages leading from the valve chambers to the piston chamber, and valves in the valve chambers controlling the flow of pressure fluid from the supply passage to the inlet passages.

6. In a fluid actuated rock drill, the combination of a cylinder having a piston chamber and a piston in the piston chamber, a rifle bar for rotating the piston, a head on the rifle bar, a valve chest in the cylinder forwardly of the head and having a bore to form a continuation of the piston chamber, a plurality of valve chambers in the valve chest, a supply passage conveying pressure fluid from a source of supply to the valve chambers, means for restricting the flow of pressure fluid into the valve chambers, inlet passages leading

from the ends of the valve chambers to the corresponding ends of the piston chamber, and valves in the valve chambers alternating between the inlet passages for controlling communication between said inlet passages and the supply passage.

7. In a fluid actuated rock drill, the combination of a cylinder having a piston chamber and an exhaust port and a piston in the piston chamber controlling the exhaust port, a valve chest in the cylinder comprising a pair of end plates and an intermediate plate, a plurality of valve chambers in the intermediate plate, valve seats on the end plates in coaxial alignment with the valve chambers, a supply passage leading from a source of pressure fluid supply to the valve chambers and in constant communication therewith, means for restricting the flow of pressure fluid from the supply passage to the valve chambers, inlet passages leading from the valve chambers to the ends of the piston chamber, and disk valves in the valve chambers for controlling the flow of pressure fluid from the supply passage to the inlet passages.

In testimony whereof we have signed this specification.
